UNITED STATES PATENT OFFICE.

MELBERN BERNIE BULLA, OF EL PASO, TEXAS.

AUTOMATIC TRAIN-STOP.

1,165,152.

Specification of Letters Patent. Patented Dec. 21, 1915.

Application filed May 1, 1915. Serial No. 25,177.

To all whom it may concern:

Be it known that I, MELBERN B. BULLA, a citizen of the United States, and a resident of El Paso, in the county of El Paso and State of Texas, have invented a new and Improved Automatic Train-Stop, of which the following is a full, clear, and exact description.

This invention relates to railway appliances, and has particular reference to automatic devices for causing the operation of certain signal and indicating devices in the locomotive cab or its equivalent when a danger signal is passed.

Among the objects of the invention is to provide a construction including the devices carried by the locomotive and comprising an alarm gong, connections with the train air line, and main and auxiliary electric circuits serving first to sound the alarm and subsequently to open the train line when the engineer, through carelessness or incapacity, allows his locomotive to run past a danger point.

A further object of the invention is to provide a pneumatically operated means for shutting off the steam, the air supply for this means being received from the train line.

The foregoing and many other objects of the invention will hereinafter be more fully described and claimed and illustrated in the drawings forming a part of this specification in which like characters of reference indicate corresponding parts in all the views, and in which—

Figure 1 is a vertical longitudinal section of a locomotive showing my improvements applied thereto; Fig. 2 is a front elevation of a semaphore indicating one form of electrical connections therewith for use in connection with my locomotive appliances; Fig. 3 is a detail view of the means for automatically shutting off the steam; and Fig. 4 is a detail view of another of the automatically operated power devices.

The several parts of this device may be made of any suitable materials, and the relative sizes and proportions, as well as the general design of the mechanism, may be varied to a considerable extent without departing from the spirit of the invention hereinafter more fully described and claimed.

Referring more particularly to the drawings, I show a representation of a loco-

motive, and by the term locomotive I mean to cover any vehicle adapted to be equipped with and have its operation controlled by the improved devices constituting this invention. At any convenient place on the locomotive is carried a shoe 10 insulated from the framework and having a wire 11 leading to a battery 12.

At 13 is an electromagnet having an armature 14, and the magnet 13 is connected to the battery by a wire 15 and the circuit through the magnet is completed by a wire 16 grounded at 17. When the armature 14 is attracted by the magnet 13, it strikes the gong 18, thereby sounding an audible alarm. This alarm constitutes a portion of an auxiliary circuit from the battery through the magnet, thence through a wire 19, lever 20 and wire 21 connected with the main wire 11 on the opposite side of the battery.

The danger signal is represented by the semaphore arm S in horizontal position at which time a bridge 21 closes the gap between the contact points 22 between a metal wire brush 23 adjacent the track and the ground 24. The brush 23 is insulated from the ground, and when the roadside signal is set at safety, the connection from the brush to the ground will be broken at the points 22 through the action of the rod 22^a, and hence contact of the shoe 10 with the brush will have no effect upon the devices carried by the locomotive.

25 indicates the usual train air line and 26 is a branch or auxiliary line leading therefrom but normally closed by means of a valve 27 having an arm 28 controlling it.

At 29 I show an air cylinder having a piston 30 movable against a spring 31 and having a piston rod 30' connected to the outer end of said arm 28. The piston 30 is normally forced rearwardly within the cylinder 29 by virtue of the spring 31, and thereby the valve 27 is held normally closed. An air pipe 32, however, leads from the auxiliary pipe 26 into the rear end of the cylinder 29, but this auxiliary pipe 32 is normally closed by means of a valve 33 having an arm 34 and a link 35 connecting it to the free end of the arm 14. A spring 36 acts upon the arm 14 to hold it remote from the magnet 13 and serving through the link 35 and arm 34 to hold the valve 33 closed. The normal position of the piston 30 is indicated in dotted lines in Fig. 4, and adjacent the same at such time the inner surface of the cylin-

der is provided with a slight groove or bypass 29' which will allow any slight leakage of air through the pipe 32 during the running of the train to pass the piston and hence such air will not accumulate in the cylinder and cause the piston to move against the force of the spring to undesirably open the valve 27. When, however, the arm 14 is drawn toward the magnet and the 10 gong is struck thereby, the valve 33 will be opened far enough to admit air through the pipe 32 into the cylinder 29 which, acting upon the piston 30, will cause the arm 28 to swing in a counter-clockwise direction 15 and open the valve 27. In order to keep a record of the number of times the locomotive signal devices are operated by the passage of a signal set at danger or an equivalent condition, I employ an indicator 20 37 with a link 38 connecting it to the arm 28. At 39 I show another air cylinder having a piston 40 acted upon by a spring 41 serving to hold the piston in or adjacent the rear end of the cylinder. This piston 40 25 is loosely connected to a rod 42 pivoted to the engineer's throttle lever indicated diagrammatically at 43. Said connection between the piston 40 and the rod 42 is had through a sleeve 42^a, the sleeve 42^a being 30 carried by the piston and into which the rod 42 extends loosely. It will be understood therefore that the rod 42 as shown herein will not interfere with the ordinary manipulations of the lever 42 by the engineer, but when the piston is operated by the 35 automatic means herein provided, the throttle lever will be operated simultaneously. The cylinder 39 is connected to the auxiliary air line by means of a pipe 44, and simultaneously with the admission of air from the auxiliary pipe into the cylinder 29, admission is made into the cylinder 39 and hence the air pressure from the auxiliary line will serve to automatically shut off the steam 40 45 while the air motor 29 is operating to open the train air line at the valve 27. The motor cylinder 29 is provided with a valve 45 adjacent its rear end normally held closed by the lever 20 when the lever is in 50 position to bridge the contact points of the circuit wires 19 and 21.

With the devices arranged and connected as described above, the operation may be briefly summarized as follows: With the 55 semaphore set at danger and the bridge 21 connecting the contact points 22, if the locomotive in disregard of the danger signal proceeds to pass it, the shoe 10 will come into contact with the brush 23 and the 60 energy from the battery 12 acting through the magnet 13 will cause the arm 14 to impinge against the gong 18 and immediately open the valve 33, allowing the air under pressure to escape from the air line 65 and act to force the pistons 30 and 40 both

forwardly. The arm 20 of the bleeding valve 45 being in its normally closed position connecting the lines 19 and 21 and the arm 14 being now in contact with the wire 19, the energy from the battery will be maintained through the magnet, and through the arm 14, line 19, lever 20 and line 21 with the main line 11, even though the locomotive will have passed beyond the brush 23. Thus, the pistons 30 and 40 will both 70 be given full forward impulses due to the flow of compressed air past the valve 33 with the result that the valve 27 will be opened by the piston 30 and the throttle will be closed by the action of the piston 80 40. The train will, therefore, be brought to a stop automatically and a record of the circumstance will be made on the indicator 37. When the engineer swings the lever 20 forwardly to bleed the air from the cylinder 29, the spring 31 will restore the piston 30 to its normal rearward position and thereby close the valve 27. This movement of the lever 20 breaks the contact between the wires 19 and 21, deenergizing the magnet 13 and permitting the spring 36 to restore the arm 14 to its normal forward position with the hammer away from the gong and breaking the circuit between the arm and the wire 19. 95

I claim:

1. In an automatic train stop, the combination of a battery, a main circuit in which the battery is located and closed by the passage of a locomotive past a danger signal, a magnet in said circuit, an armature arm drawn toward the magnet when the same is energized, said arm serving to ring a gong and open a normally closed air valve, an auxiliary circuit of which said arm is a part and completed by the attraction of the arm as aforesaid and operative irrespective of the position of the locomotive, a pneumatic motor set into operation by the opening of said valve, and means to subsequently relieve the air pressure from the air motor and simultaneously break the auxiliary circuit, substantially as set forth. 105

2. In an automatic train stop, the combination of a main circuit including a battery, means to close the circuit by the passage of a locomotive past a danger signal, an electromagnet in said circuit, a pivoted armature arm acted upon by the magnet when energized, said arm serving to sound a 115 gong and complete a circuit from the battery through an auxiliary circuit irrespective of the position of the locomotive, an air pipe charged with compressed air, a valve normally closing said pipe and having pivoted link connection directly with said armature arm, said valve being normally closed but being opened by the attraction of said arm as aforesaid, a pneumatic motor cylinder positioned to receive air from said 125 130

air pipe when the valve aforesaid is opened, a piston in the cylinder acted upon by the air pressure when admitted thereto on the opening of the valve, movable members set into operation by said piston, a normally closed bleeding valve adjacent the piston when it is in normal position, said bleeding valve having a lever constituting a portion of said auxiliary circuit whereby when the air is bled from the cylinder the auxiliary circuit will be broken, and means to re-

store the armature arm to its normal position remote from the magnet for the breaking of the circuit.

In testimony whereof I have signed my ¹⁵ name to this specification in the presence of two subscribing witnesses.

MELBERN BERNIE BULLA.
